UNITED STATES PATENT OFFICE

JOHN HENRY RATHBONE AND HERBERT RATHBONE, OF STRETFORD, ENGLAND

HAND-PROPELLED PADDLE BOAT

Application filed April 20, 1929, Serial No. 357,671, and in Great Britain May 17, 1928.

This invention relates to improvements in paddle boats of the type having a pointed nose or bow and a square stern and in which the paddles are operated by hand through cranks, such boats being used as pleasure boats on lakes and similar stretches of water.

The object of the invention is to produce a boat which will be safer than hitherto constructed, which is foolproof and practically uncapsizable, which has absolute freedom in the construction of any portion of parts liable to cause injury to the occupants, which will be easier to operate, which will be more comfortable to the occupants and which will allow each paddle to be operated by a separate person.

According to the invention the boat is constructed with a pointed nose or bow, a square stern, a flat bottom, floor boards, covering all or part of the bottom and bearers, two sets one near the stern facing the bow of the boat and the other near the bow facing the stern of the boat, the stern seat being provided with a back rest, a forward deck covering in the bow of the boat from the stern to the forward seat and forming a back rest for such seat, and a separate crank and handle for operating each paddle wheel.

The invention will be described with reference to the accompanying drawings:—

Fig. 1 is a plan of the boat.

Fig. 1^a is a plan view of paddle box.

Fig. 2 is a longitudinal section of the boat.

Fig. 3 is a transverse section thereof.

Fig. 4 is an enlarged perspective view of one of the paddles.

Fig. 5 is an enlarged sectional view of one form of packing gland for the paddle shaft.

Fig. 6 is an end elevation of one of the plates of same.

Fig. 7 is an enlarged sectional view of another form of packing gland for the paddle shaft.

Fig. 8 is an end elevation of one of the plates of same.

The boat is constructed with pointed nose or bow A, a square stern B, a flat bottom C,

carried by the transverse bearers c and with vertical or approximately vertical sides D curved from the bow to the stern. A seat E carried on brackets e affixed to the sides of the boat is arranged near the stern and is provided with a back rest E¹ preferably affixed to the sides of the boat. The seat E faces towards the bow of the boat. A second seat F carried on brackets f affixed to the sides of the boat is arranged near the bow of the boat and the front of the boat forward of the seat F is covered in with boards G to form a forward deck, the edge g of which also serves as a back rest for the forward seat F.

The bottom C of the boat is covered by boards C¹ which also cover the transverse bearers c and provide a clear space between the seats E and F. The boards extend the whole distance between the seats E and F so that should any water get into the boat it will not come into contact with the occupants.

The seats E and F are wide enough to be each occupied by two persons and as the sides D of the boat are vertical or approximately vertical there is as much room at the bottom as at the top, thus allowing sufficient space for the legs of the occupants.

Two paddles H are arranged one at either side of the boat sufficiently near to the seat E so that they can be actuated by the occupant or occupants thereof. Each paddle (see Fig. 4) is constructed with four blades h mounted on a square spindle h¹.

The blades h are carried in pairs one at each end of a pair of flat metal strips bolted to the square spindle h¹. The strips h² carrying one pair of blades are straight and the strips h³ carrying the other pair of blades are bent in the plane of the blades so that they will pass inside the other pair of strips h² at the centre. The blades h are formed of flat material bolted, riveted or otherwise affixed to the strips.

The spindle h¹ projects into the boat through the side being circular in cross section at this end and a crank or handle H¹ is attached to the end of the spindle inside the boat. A suitable water-tight packing or

gland is arranged around the spindle h^1 where it passes into the boat to prevent water entering the boat around the spindle.

One form of water-tight packing is shown in Figs. 5 and 6. It comprises a circular plate K affixed to the outside of the boat and having a cylindrical flange k provided with a screw thread on its outer surface, the shaft h^1 passing through the centre of the plate, and a second circular plate K^1 affixed to the inside of the boat and having a flange k^1 the inner diameter of which is the same as the outer diameter of the flange k so that it can be screwed on to the latter. A plug or nut k^2 is screwed into the flange k^1 to compress the resilient packing material K^2 between it and the end of the flange k to form a tight packing around the shaft h^1 . The ends of the plug k^2 and flange k adjacent to the packing K^2 are preferably chamfered as shown. The plates K^1 and K^2 are bolted to the side of the boat by the bolts k^3 .

The watertight packing shown in Figs. 7 and 8 comprises two rectangular plates K^4 and K^5 with central cylindrical flanges k^4 and k^5 of equal diameter through which the shaft h^1 passes. A resilient packing K^2 is placed between the chamfered ends of the flanges k^4 and k^5 and is compressed by the bolts k^3 which hold the plates k^4 and k^5 in position.

The paddles H are housed in paddle boxes L which are semi-circular in shape and are carried on boards or plate l projecting outwards from the sides of the boat. These plates or boards l are connected both at the front and back to the sides of the boat by diagonally arranged bars or stays M arranged as shown in either Fig. 1 or Fig. 1^a which serve as buffers to guard the paddles and paddle boxes. A convex iron band M^1 may be arranged along the edge of the board l to reinforce it.

What we claim as our invention and desire to protect by Letters Patent is:—

A paddle boat of the type referred to having a pointed bow, a square stern, a flat bottom, transverse bearers and floor boards covering the bottom and bearers, two seats one near the stern facing the bow of the boat and the other near the bow facing the stern, approximately vertical sides to allow of the seats being occupied by two persons, a back rest for the stern seat, a forward deck covering in the bow of the boat to the forward seat and forming a back rest for such seat, a paddle wheel on each side of the boat, shafts passing through the sides of the boat upon which the paddle wheels are mounted, a cranked handle directly mounted on each shaft by which it is rotated, circular paddle boxes projecting from the sides of the boat, plates upon which the paddle boxes are carried and diagonal stays serving as buffers to guard the paddles, boxes connecting the

plates fore and aft to the sides of the boat and water tight glands through which the shafts pass.

In testimony whereof we have hereunto set our hands.

JOHN HENRY RATHBONE.
HERBERT RATHBONE.
